ATTORNEY

UNITED STATES PATENT OFFICE

HERBERT SCHRADER, OF WHEELING, WEST VIRGINIA, ASSIGNOR, BY MESNE ASSIGNMENTS, TO CONTINENTAL CAN COMPANY, INC., A CORPORATION OF NEW YORK

CAN

Application filed May 31, 1928. Serial No. 281,726.

This invention relates broadly to cans and pails, and more specifically to a can or pail of slip cover type.

The primary object of the invention is to provide a can of the character employed as containers for non-liquid products, having a readily removable slip cover and embodying simple means whereby the cover is retained against chance displacement upon the can body.

In describing the invention in detail, reference is herein had to the accompanying drawings, in which—

Figure 1 is a top plan view of the invention, partly in broken section;

Figure 2 is a section on line 2—2, Fig. 1; and

Figure 3 is a detail section on line 3—3, Fig. 2.

Referring to said drawings, 1 designates a can body which has an inwardly turned roll 2 formed on its upper end. Said roll is adapted to receive in seated relation there-to the rim portion 3 of a slip cover 4 which 25 has a circumferential depending flange 5 for closely embracing the can body adjacent to its said upper end.

Provided in the roll 2 inwardly of the vertical plane of the body 1 is a plurality 30 of similar relatively spaced recesses 6 which are preferably formed by cutting away relatively short lengths of the metal of the roll, thus to form vertical passageways through which may unobstructedly pass lugs 7 35 formed in similarly spaced relation on the under side of the can cover 4.

The rim portion 3 of said can cover 4 is shaped to form a downwardly facing channel which, as shown at the left in Fig. 2, 40 is adapted to receive snugly therein the roll 2 of the can body, said channel being defined on its outer side by the depending flange 5 and on its inner side by a substantially vertical wall 8 which extends down- 45 wardly to a level slightly below that of the under side of said roll. The lugs 7, herein-before referred to, are formed at properly spaced intervals by pressing the lower end of the wall 8 outwardly toward the flange 50 5. Such pressing is effected in such manner

that the metal of the cover is slightly stretched at and adjacent to said lugs.

In applying the cover, the lugs are entered within the can body through the recesses 6, following which the cover is slightly rotated relative to the can body for positioning the lugs in closely underlying relation to the roll 2 at points located laterally with respect to said recesses, as shown in the drawings. In such position, the cover is effectually retained against chance displacement. Manifestly, removal and re-application of the cover may be conveniently effected by hand without marring of or injury to either the can or the cover. The exterior 65 surface of the flange 5 may be knurled or otherwise roughened to facilitate hand rotation of the cover.

What is claimed is—

In a can or pail, a container body having 70 an inwardly turned terminal roll at its upper end, said roll having formed therein a plurality of recesses, which recesses extend only part way through said roll, leaving a continuous portion of the roll at the outer 75 peripheral edge of the container body, and a slip cover for said can body, said cover having a depending flange extending down along the outer wall of the can body, and having a central depressed portion adapted 80 to fit within the embrace of the terminal roll and to form a channel adapted to receive said roll, said cover having laterally projecting lugs formed in the wall thereof adjacent said roll, which lugs are adapted to 85 pass through the recesses and upon a turning of the cover relative to the body to be placed beneath said roll for securing said cover to said body.

In testimony whereof, I affix my signature. 90
HERBERT SCHRADER.
